ARTHUR RONALD TRIST, OF LONDON, ENGLAND, ASSIGNOR, BY MESNE ASSIGNMENTS,
TO PANTONE CORPORATION, OF NEW YORK, N. Y., A CORPORATION OF DELAWARE

PLATE MOUNTING

Application filed January 24, 1930. Serial No. 423,048.

This invention relates to the art of printing and in its more specific aspects aims to provide a structure whereby printing plates may be held firmly against displacement.

5 It is an object of the invention to provide a structure of this character which will embody relatively few parts, each individually simple and rugged in construction, these parts being capable of manufacture and assembly to furnish a mechanism operating over long periods of time with freedom from difficulties.

10 A further object is that of constructing a plate-retaining mechanism by means of which, for example, a number of plates may be applied to the cylinder of a press, such application being achieved in a minimum amount of time, without it being necessary to exercise that degree of care which has heretofore been essential in "setting up" the plates within a press.

15 A further object of the invention is that of providing such a mechanism and in which the plates will be retained against any probability of displacement either with respect to each other or with respect to the cylinder or other member mounting the same. Moreover, as a result of this invention, the plates, when desired, may readily be removed from association with the press and a new plate-set may be substituted therefor in a minimum amount of time.

20 With these and further objects in mind reference is had to the attached sheet of drawings illustrating practical embodiments of the invention and in which:—

Figure 1 is a face view of a cylinder;

Fig. 2 is an enlarged fragmentary, partly sectional view thereof;

Fig. 3 is an enlarged sectional view taken along the lines 3—3 of Fig. 1, and

Fig. 4 shows a form of construction slightly different from that depicted in Fig. 2.

25 In these views, and in the subsequent specification, the invention has been described in connection with printing presses of the cylinder type. While in most respects the invention is primarily intended for use in this association, it will be understood that it may

be employed in connection with various other forms of imprinting mechanism.

Thus, in these views the numeral 5 indicates the body of a cylinder, which preferably carries a fixed ring 6 and a shiftable ring 7 upon its main body. This cylinder also carries, adjacent its ends, shiftable rings 8 which lie adjacent to the end flanges 9 of the cylinder.

30 In association with the cylinder it is intended that plates 10 are to be employed, these plates being relatively thin and constructed in any desirable manner. Preferably, they conform, when removed from the press, substantially to the curvature of the cylinder, 60 but this need not necessarily be the case, and these plates have edge portions 11 which are beveled. At this time it will be appreciated that while in most instances it is desirable to employ a thin plate, as will hereinafter appear, the invention may be employed as advantageously in connection with relatively thick plates.

35 The rings 6, 7 and 8 are, in the case of thin plates, undercut as has been indicated at 12 75 and to a degree corresponding to the bevel 11 of the plates, or these rings may have their edges otherwise disposed with a view to cooperating effectively with the plates. However, it is preferred that the construction 80 herewith illustrated be employed and the diameter of the rings is such that they preferably extend just short of the plane of the plate face. Projecting between the rings are strips 13 which are similarly formed with a 85 view to cooperating with and retaining the end edges of the plates. Obviously, these strips may be shifted if desired, to accommodate, for example, upon the cylinder, plates which extend throughout nearly one-third 90 instead of substantially one-half of the cylinder circumference.

40 Adjacent the points at which the cylinder mounts the rings 7 and 8, it is preferably curved or reduced to accommodate the bodies 95 of these rings and at this time it will be noted that according to the present invention it is preferred to have the base of these reduced or grooved portions inclined, as has been indicated at 14, and the under faces of the rings 100

are correspondingly inclined as at 15 so that a tight fit between the cylinder and rings may be assured.

With a view to shifting the rings 8, the 5 flanges 9 may be formed with openings through which pins 16 extend, these pins being secured to or, in fact, forming an integral part of bull rings 17 and lying immediately adjacent the rings 8. Beyond the flange 9 the 10 cylinder may present a threaded portion 18 upon which a collar 19 is mounted which has bearing with the inner ends of the pin 16. Consequently, as the collar is rotated around the relatively coarse thread 18 the pins, together with the rings 17, will be forced inwardly or moved outwardly to correspondingly move, in each instance, the ring 8.

Thus, a further advantage achieved by the present invention will be apparent. More 20 particularly, perfect plate registration will be assured. In other words, with a cylinder or other plate receiving surface provided in accordance with the teachings of the present invention it will be feasible for an operator 25 to apply any number of plates thereto with assurance that these plates will occupy not alone proper positions with respect to each other but also with respect to the plate receiving surface. As a consequence it is practicable to dispense almost entirely with the 30 plate and image registering operation as it has been heretofore understood and thus a great amount of time and expense will be saved. In this connection it will be understood 35 that it will be a relatively easy matter to have the images appear in identical or properly related register positions upon the several plates which would comprise a printing form.

40 While continuous rings may be employed, it is preferred that each of the rings present a split body and with a view to coupling the end portions of these members they may, as shown in Fig. 3, present overlapping portions 45 20 formed with grooves and ribs 21 which interlock. To prevent displacement of the parts a strip 22 may be secured within a recess formed in the ring body and overlapping the end joint thereof so that all difficulties in 50 this connection are avoided.

In certain instances, after the rings have been released, they might tend to drop, i. e. assume positions eccentric with respect to the axis of the cylinder. With a view to overcoming difficulties in this connection, spring-pressed pins 23 or their equivalents may bear 55 against the inner edges of the rings to assure the maintenance of the latter in positions concentric with respect to the cylinder. Accordingly, with the rings released, they will at all times be in such condition that plates may readily be applied to the cylinder.

Considering the operation of this mechanism it will be understood that with the rings 60 7 and 8 retracted it will be a very simple mat-

ter for an operator to simply position plates upon the cylinder and to have their edges extend below the under-cut portions or the equivalents of the ring 6 and the strips 13. Now, by simply shifting the ring 7, the plates thus positioned may be locked against movement and thereupon plates may be disposed beyond the ring 7, which plates will be retained in position by shifting the ring 8 inwardly in the manner afore described. Obviously, plates to the left of ring 6, as viewed in Figure 1, may be positioned at any desired time by simply applying them to the cylinder in the manner afore described and shifting the ring 8 inwardly. The removal of the plates from the cylinder will also be apparent in that, by simply reversing the foregoing operations the plates are free to be moved out of contact with the cylinder body.

Obviously, in certain instances, it may be desired to utilize a ring-shifting structure slightly different from that shown in Figures 1 and 2. Numerous equivalents will be apparent to those skilled in the art. For example, as shown in Fig. 4, the flange 9 may be formed with a groove 23' capable of accommodating a collar 24, the edge of which is screw-threaded, as at 25, to cooperate with corresponding threads formed in the outer wall of the groove 23. The inner edge of this collar will bear against the inner ends of the pins in order to again effect a shifting of the bull rings and the clamping rings in the manner afore described.

In conclusion it will be understood that numerous changes in construction and rearrangement of the parts might be resorted to without departing from the spirit of the invention as defined by the claims, and from the foregoing it will be appreciated that, among others, the objects specifically afore brought out are accomplished.

Having described my invention, what I claim as new and desire to secure by Letters Patent is:—

1. A printing press including, in combination, a cylinder to receive a plate, a ring disposed adjacent one of the ends of said cylinder and movable with respect thereto, said ring overlapping an edge portion of said plate to retain the same in association with said cylinder, means for shifting said ring, means cooperating with the further edge of said plate to retain the same against displacement and resilient means associated with said cylinder and cooperating with said ring to maintain the same in substantially concentric position with respect to the axis of said cylinder.

2. A printing press including, in combination, a cylinder to receive a plate, a ring disposed adjacent one of the ends of said cylinder and movable with respect thereto, said ring overlapping an edge portion of said plate to retain the same in association with said cylinder, means for shifting said ring, means

cooperating with the further edge of said plate to retain the same against displacement, said ring including a split body presenting overlapping end portions and means for locking said end portions against relative movements.

3. In a printing press, in combination, a cylinder to receive a plate, a ring cooperating with one of the plate edges to maintain the same against displacement with respect to said cylinder, means cooperating with a further plate edge to retain the same against displacement with respect to said cylinder, said ring being shiftable with respect to said cylinder and means for shifting said ring into retaining engagement with the edge of a plate and cooperating wedging surfaces between said cylinder and ring for limiting the projection of the latter along said cylinder.

20 4. In a printing press, in combination, a cylinder, a fixed ring mounted by said cylinder and presenting undercut edge portions to overlap the beveled edge portions of a plate mounted upon said cylinder, a further 25 ring movable along said cylinder and also presenting undercut edge portions for cooperation with a further edge of said plate and an additional ring mounted by said cylinder and beyond one of said first named rings 30 and adjacent the end edge of the cylinder body, the adjacent edges of said last named ring and the ring in proximity to which it is disposed being also undercut to accommodate between them the edges of a further plate, an end flange for said cylinder and being formed with openings, a bull ring interposed between said last named ring and flange and means extending through said 35 openings and cooperating with said bull ring to shift the latter and said last named plate retaining ring to secure both plates against displacement with respect to the cylinder.

ring and the ring in proximity to which it is disposed being also undercut to accommodate between them the edges of a further plate and means for shifting said last named ring along said cylinder to retain both of 70 said plates between said rings.

5. In a printing press, in combination, a cylinder, a fixed ring mounted by said cylinder and presenting undercut edge portions to overlap the beveled edge portions of a 75 plate mounted upon said cylinder, a further ring movable along said cylinder and also presenting undercut edge portions for cooperation with a further edge of said plate and an additional ring mounted by said cylinder and beyond one of said first named rings 80 and adjacent the end edge of the cylinder body, the adjacent edges of said last named ring and the ring in proximity to which it is disposed being also undercut to accommodate between them the edges of a further plate, an end flange for said cylinder and being formed with openings, a bull ring interposed between said last named ring and flange and means extending through said 85 openings and cooperating with said bull ring to shift the latter and said last named plate retaining ring to secure both plates against displacement with respect to the cylinder.

In testimony whereof I affix my signature. 90
ARTHUR RONALD TRIST.
